UNITED STATES PATENT OFFICE.

ALFRED COTTON, OF ST. LOUIS, MISSOURI, ASSIGNOR TO HEINE BOILER COMPANY, OF ST. LOUIS, MISSOURI, A CORPORATION OF MISSOURI.

SUPERHEATER BOILER.

Application filed March 12, 1923. Serial No. 224,470.

This invention relates to water tube boilers of the kind that are equipped with water tubes arranged horizontally or substantially so, and a radiant heat superheater.

5 The object of my invention is to provide a water tube boiler of the general type referred to that is exceptionally efficient and which is constructed in such a manner that the superheater can be cleaned quickly and 10 easily without shutting down the boiler.

To this end I have devised a boiler that comprises water tubes arranged in a horizontal or substantially horizontal position, preferably inclined upwardly and rearwardly 15 from the front wall of the boiler setting, a furnace under said tubes, a radiant heat superheater at the rear end of the furnace arranged in a rearwardly and upwardly inclined position so as to cause the heat from 20 same to be thrown upwardly and forwardly towards the water tubes, and clean-out openings in the rear wall of the boiler setting at the upper end of the superheater, through which a cleaning tool can be introduced 25 without shutting down the boiler, so as to remove dust and soot which collects on the superheater.

Figure 1 of the drawings is a vertical longitudinal sectional view of a superheater boiler constructed in accordance with my 30 present invention.

Figure 2 is a detail sectional view of one 35 of the clean-out openings, showing the door for said opening in its open position and in its closed position.

Figure 3 illustrates a cleaning tool that can be used for removing soot and dust from the superheater.

Figure 4 is a transverse sectional view of 40 a portion of the superheater, illustrating how the cleaning tool is used; and

Figure 5 is an elevational view of several of the clean-out doors and the frames on which they are mounted.

45 Referring to the drawings which illustrate the preferred form of my invention, A designates the water tubes of the boiler which may be arranged in a horizontal or slightly inclined position, B designates the rear water legs or headers, C designates a furnace 50 arranged under said water tubes and D designates as an entirety a superheater of the radiant heat type that is arranged at the rear end of the furnace C in a rearwardly and upwardly-inclined position, so as to

cause the heat from same to be thrown upwardly against the tubes A. Owing to the fact that the superheater D is arranged in an inclined position, considerable dust and soot collects on same when the boiler is in 60 operation, and in order that said dust and soot may be removed easily and without the necessity of cutting the boiler out of service, I arrange clean-out openings E in the rear wall of the boiler setting adjacent the upper 65 end of the superheater D, so as to permit a cleaning tool F to be inserted through said clean-out openings and moved longitudinally of the top surface of the superheater to 70 scrape off the soot and dust, as shown in Figure 1.

The superheater D herein illustrated is of the same general construction as one type of radiant heat superheater that is now in general use and is composed of superheater tubes 75 1 arranged in parallel relation and surrounded by metal casings 2 separated from each other by refractory dividing members or bricks 3 that project upwardly slightly above the top surfaces of the heat absorbing 80 metal casings 2 that surround the superheater tubes, the top sides or faces of said metal casings 2 being flat, as shown in Figure 4. The heat absorbing casings 2 that surround the superheater tubes, and the bricks 3 85 that are arranged between said casings, are carried by a supporting structure, designated as an entirety by the reference character G, which may be of any suitable form, and a metal housing H is arranged in the rear 90 wall of the boiler setting so as to cover the underside of the superheater D. As previously stated, clean-out openings E are provided so as to enable the cleaning tool F to be used for scraping off the soot and dust that 95 collects on the top faces of the heat absorbing casings 2 of the superheater that surround the superheater tubes 1. These clean-out openings E are arranged below the lower ends of the rear water legs or headers B so that the cleaning tool F may be used without shutting down the boiler, and each of said clean-out openings is provided with a door or cover I that is normally closed, as shown in broken lines in Figure 2, but which is 100 capable of being moved into the position shown in full lines in Figures 2 and 5, when it is desired to use the cleaning tool. The clean-out doors I may either be of the hinged 105 type or any other preferred type, and the 110

supporting means for said doors may either be formed by a single casting arranged transversely in the rear wall of the boiler setting, or by individual castings I', as herein illustrated.

In a boiler of the construction above described access to the exposed surface of the superheater through the clean-out openings E is very easy and convenient and the superheater can be kept perfectly clean with very little trouble while the boiler is in operation, the clean-out openings being so arranged that the whole length of the superheater can be viewed through same, and a suitable tool introduced through said openings to remove the dust and scrape the superheater elements perfectly clean. Accordingly, it is possible with such a boiler to easily maintain the superheater in such condition that the superheat will always be kept at the proper amount, a thing that is not possible in a superheater boiler which is of such design that it is necessary to shut down the boiler during the operation of removing dust and soot from the exposed surface of the superheater.

Having thus described my invention, what I claim as new and desire to secure by Letters Patent is:

1. A superheater boiler provided with longitudinally-disposed water tubes, a furnace under said tubes, a superheater of the radiant heat type arranged at the rear of said furnace in a rearwardly and upwardly inclined position so that the heat from same will be thrown upwardly and forwardly against said water tubes, and clean-out open-

ings in the rear wall of the boiler setting arranged at the upper end of said superheater so that a cleaning tool can be inserted through same and moved over the exposed face of the superheater when the boiler is in operation.

2. A water tube boiler provided with water tubes that are inclined rearwardly and upwardly away from the front wall of the boiler setting, a furnace under said tubes, a superheater at the rear end of said furnace comprising tubes that are inclined upwardly and rearwardly and heat absorbing elements combined with said tubes, and clean-out openings in the rear wall of the boiler setting arranged at the upper end of said superheater so as to enable a cleaning tool to be introduced through same and moved longitudinally over the top surfaces of said heat absorbing elements.

3. A water tube boiler provided with water tubes that are inclined rearwardly and upwardly with relation to the boiler setting, a furnace under said tubes, a superheater of the radiant heat type arranged at the rear end of the furnace in an upwardly and rearwardly inclined plane that passes below the rear water legs or headers of the boiler, clean-out openings in the rear wall of the boiler setting arranged at the upper end of the superheater, movable doors or closures for said openings, and a metal housing arranged in the rear wall of the boiler setting so as to cover the underside of said superheater.

ALFRED COTTON.
